ABSTRACT OF THE DISCLOSURE

A machine for destroying discarded railroad cross-ties in which a rotary comminutor, having an upwardly directed feed opening and an infeed chute leading thereto, is carried by a self-propelled car for movement along a railroad track to various locations where the ties are to be picked up. The car also carries a tie pick-up means in the form of a boom having a controllable grapple suspended therefrom, with the grapple rotatable about a generally vertical axis so that the tie picked up and suspended therefrom may be rotated and positioned to bring their flat sides into position for flush engagement with an infeed conveyor on which they are deposited for delivery into the infeed chute. The ties are delivered in an endwise direction upwardly and diagonally through a feed opening in one side of the chute and across the vertical infeed passage thereof, and then, by action of the conveyor, are tilted about a horizontal fulcrum to a vertical position for movement downwardly through the vertical infeed passage into the comminutor. After being reduced to small chips in the comminutor, the ties are discharged through an opening in the comminutor bottom into a pneumatic conveyor leading to the intake of a blower which then discharges them through a suitable spout.

This invention relates to a comminuting machine and more particularly to improvements in the infeed mechanism of such a machine.

In various types of wood comminutors or chippers, a length of wood to be comminuted is fed through a guide chute into a rotary cutter head or comminutor in a direction generally radially to the rotational axis of the cutter head, to be thereby formed into small chips of wood for disposal or for use in various ways. In many such machines the lengths of wood to be comminuted are delivered manually into the guide chute of the comminuting machine.

It is a particular object of the present invention to adapt such a comminuting machine for use in the comminuting of discarded railroad ties. It will be readily apparent that because of the large size and weight of the railroad ties, it is not feasible to manually raise and manipulate them for feeding into the comminutor. With this in mind, the invention contemplates the provision, in combination with the comminuting machine, of an infeed conveyor and conveyor chute wherein the arrangement is such that after being placed upon the conveyor by suitable grapple or other mechanical means, the tie is conveyed upwardly at a vertical inclination or slope into the similarly sloping infeed passage of a guide chute. The guide chute is also formed with a vertical passage communicating downwardly with the casing the rotary comminutor and intersecting said sloping infeed passage. Special provision is made for feeding the ties on the conveyor diagonally up into the inclined infeed passage and then utilizing the conveyor to tilt them about a fulcrum within the chute so as to switch them into the vertical infeed passage to thereafter move by gravity downwardly through said passage and into operative engagement with the comminutor head.

Only the preferred embodiment of the invention is specifically illustrated and described in this application, though other and different embodiments will be made obvious thereby to persons of ordinary skill in the art.

In the accompanying drawings, FIG. 1 is a side elevation of a comminuting machine and its associated infeed mechanism, same being supported on a railway flat car for movement along the rails to pick up and comminute discarded ties.

FIG. 2 is a section along the line 2—2 of FIG. 1; and, FIG. 3 is an enlarged detail section along the line 3—3 of FIG. 1.

Referring first, generally, to the construction shown in FIG. 1, the invention therein is shown as mounted on a self-propelled railway vehicle 10 which is supported on flanged wheels 12 and 14 for movement along the rails R and, preferably, is propelled through power furnished from an internal combustion engine 16 and transmitted to the drive wheels 12 in any suitable manner and under any conventional controls. The mechanism, preferably, is controlled by an operator whose seat 17 is located within the cab 18, all to the end that the vehicle may move along the railroad track and be brought to a stop at any desired location, so that suitable tie pick-up means P supported on the vehicle may be manipulated to pick-up the discarded ties and deliver them in succession onto the infeed conveyor 20 for delivery in an upwardly inclined path into the generally vertical comminutor guide chute 22 for delivery downwardly by gravity through said chute and into the casing 24 of a comminutor C to be operated upon by the comminutor head 26 therein. The comminutor head 26 (shown in FIG. 2) is rotatably driven from the engine 16 through the engine output shaft 28 which is connected by the flexible coupling 30 to the driven shaft 32 which rotatably supports the cutter head. As the ties are disintegrated by the comminutor C, the resulting wood chips fall downwardly through an opening 33, in the bottom of the comminutor casing 24 and into the pneumatic conveyor conduit 34 shown in FIGS.

1 and 2 through which they are drawn to a suction intake opening in the casing of a suitable centrifugal blower B to be discharged through a suitable swivel spout 36 either into the bushes alongside the railroad track or into a suitable vehicle. The blower B preferably is driven by its own internal combustion engine 38, the output shaft 40 of which, in turn, is connected through the flexible coupling 42 to the driven shaft 44 of the rotary blower element (not shown) housed within the blower casing 45.

The tie lifting and handling means P illustrated here, is of a conventional type such as is sometimes termed a backhoe, including a main boom 46 which is pivoted at 48 to a swingable supporting base 50 and moved about said pivot 48 by a hydraulically actuated piston and cylinder unit in conventional manner. Pivoted connected at 54 to the main boom 46 is the auxiliary boom or extension 56 which is moved about its pivot to various desired positions by means of the hydraulically actuated piston and cylinder unit 58, all as shown in FIG. 1. At the free end of the auxiliary boom is carried the tie pincers or grapple G.

The construction of a tie grapple G is best illustrated in FIGS. 1 and 3 considered together.

It will be apparent from these figures that the pincer jaws 60, which are preferably provided with protruding teeth 62 for better gripping the ties, are carried at the free ends of the rigid arms 64 which in turn are pivotally supported at 66 on brackets 68 of a cross-head 70. The arms 64 are actuated by suitable hydraulic means, not illustrated, for movement toward and away from each other to thus operatively engage and disengage the ties.

The cross-head 70 is in the form of a circular plate

having an overhanging annular lip 72 supported in spaced relation therefrom to thus establish a rotatable connection between the plate and a supporting disk 74 having a centrally located bracket 76 projecting upwardly therefrom and by which said disk is pivotally suspended at 78 from the lower end of a universal link 80 having its upper end pivoted at 82 to a suspension bracket 84 fixed to the free end of the auxiliary boom.

In order to permit angular movement of the pincer arms 60 about a vertical axis to the extent necessary to present a flat side of the tie toward the operative run of the conveyor 20, there is provided a hydraulic motor 86, the base 88 of which is bolted or otherwise affixed to the supporting disk 74 concentrically to the disk. The hydraulic motor is of a rotary or angularly moving type, having its rotary output shaft 90 disposed through the hub of the supporting disk 70 and keyed to the hub at 92, so that rotation of the shaft will rotate the plate as well as the tie grapple G supported therefrom to any of various desired angular positions. Control of the rotary hydraulic motor 86 is achieved by conventional means constituting no part of the present invention.

The feed chute 22 through which the ties are fed vertically, downwardly into operative engagement with the comminutor head 26 defines a vertical feed passage 94 as shown in FIG. 2 which communicates downwardly with the feed opening 96 in the upper end of the comminutor casing 24. In addition, the chute is formed to define a vertically inclined infeed passage 98 which medially intersects said vertical passage 94 and which defines an infeed opening 95 through the side of the chute in alignment with the upper run of the infeed conveyor 20 for reception therein of the ties.

At the juncture of the said vertical and vertically inclined infeed passages, on the side of the vertical passage remote from the infeed conveyor 20, the chute 22 is formed with a vertically inclined bottom section 100 in alignment with the upper run of the conveyor 20 for engaging and supporting the upper end portion of a tie projected upwardly and across the vertical passage 94 by the infeed conveyor, all as shown in FIG. 2.

The lower end or extremity of the sloping chute bottom portion functions as means defining a fulcrum 102 about which the tie may be pivoted as its lower end leaves the infeed conveyor to swing the tie from its inclined position to a substantially vertical position for movement downwardly by gravity through the vertical chute passage 94 and into operative engagement with the rotary comminutor head 26.

In the present embodiment, the upper end of the chute 22 is open so that the tie may be projected upwardly therethrough and freely swung from an inclined to a generally vertical position. Further, it is desirable to provide a downwardly sloping hood 104 over the infeed opening 95 substantially parallel to but spaced from the plane of the upper run or operative run 106 of the infeed conveyor 20 whereby to co-act with the sloping chute bottom section 100 in guiding the ties in their vertically inclined upward movement and in confining them to such movement until such time as the lower end of each tie is discharged from the infeed conveyor 20.

The infeed conveyor herein shown 20, and described is of the endless flexible type comprising a sprocket chain guided for movement through an endless circuit around the sprocket wheels 108 and 110 shown in FIG. 2. The sprocket wheels are supported at opposite ends of a rigid frame 112 which, in turn, is fixedly supported with respect to the infeed chute 22 and the rotary comminutor C, as by the rigid supports 114 and 116 connecting the mid-portion and the upper end portion of said frame to a frame member suitably anchored to the rotary comminutor housing 24 and by the diagonal brace or strut 120 interconnecting the lower end of the infeed conveyor frame to the main frame 10 of the vehicle.

Carried by the conveyor frame 112 on opposite sides

of the operative conveyor run 106, and projecting thereabove, are relatively parallel side walls 120 for retaining the respective ties properly positioned on the upper run of the conveyor and in alignment with the conveyor movement. Preferably, these walls 120 are interrupted at a suitable location 122 to permit a close approach of the tie grapple G to the conveyor 20 at the time of placing ties thereon so as to avoid interference between the side walls and the grapple. The infeed conveyor 20 is driven by a fluid motor 124 (FIG. 1), supported at the lower end of its frame 112 and operatively connected to the lower or drive sprocket 110 in a manner to cause the upper or operative run 106 of the conveyor to move upwardly in the direction of the arrow in FIG. 2 and thence over and around the upper sprocket 108 at the discharge end of the conveyor before commencing its return run. Obviously, the operative conveyor run 106 moves toward and in alignment with the infeed opening 95 through the adjacent lateral side of the chute 22 to project the ties into and through said opening, and in passing around the upper sprocket 108, the operative run 106 moves in an arcuate path having a substantial lateral component of movement toward the opening. For thrusting engagement with the lower end of a tie T carried on the operative run of the conveyor so as to project said tie through the infeed opening 95 into the chute 22, the conveyor chain is provided with a conveyor flight 126 rigidly affixed to one of its links and projecting outwardly therefrom substantially at right angles to the operative run of the conveyor and to the link. In order to enable the conveyor flight 106 better to withstand the very substantial thrust exerted upon it by the comparatively heavy tie T, there are provided on adjoining links abutment members in the form of L-shaped brackets 127 and 128, one of which, 127, abuts against the rear face of the conveyor flight 126, and the other of which, 128, abuts against the rear face of the first such abutment. It will be apparent that these abutments and the conveyor flight will all relatively separate during their movement around the sprockets so as not to interfere with such movement in any way.

It will be apparent that the conveyor flight 126 might be of sufficient length, or in other words, might project outwardly from the conveyor a distance substantially in excess of the thickness of the ties so as to engage first against the end of each tie during the majority of its operative movement on the conveyor and then at the time of its discharge from the conveyor to thrust against the adjoining side-wall portion of the tie whereby to kick the lower end of the tie through the infeed opening 95 into the vertical chute passage 94, at the same time swinging the tie T medially about the fulcrum 102 to switch it into the vertical feed passage 94 for movement by gravity into the comminutor C.

However, such proportion and functioning of the conveyor flight would permit the tie to exert an undesirable mechanical advantage or stress through the flight 126 on the conveyor chain 106 itself. Therefore, in the preferred embodiment of FIG. 2, the flight 126 projects outwardly from the chain by a distance which is appreciably less than the thickness of the tie T. Thus, at the time of discharge of the tie, when the flight moves around the upper conveyor sprocket 108, prior to commencing its return run, it will scrape across the end of the tie without ever engaging the adjoining side wall thereof and, in so doing, may not in all instances pivot the tie about the fulcrum 102 sufficiently to move it from above the sprocket 108 and into the vertical conveyor infeed passage 94. Therefore, in the preferred embodiment there is provided a further or auxiliary conveyor flight 130 spaced in trailing relation behind the operative conveyor flight 126 so that after the end of the tie has been disengaged by the leading conveyor flight, if its lower end still rests on the discharge end of the conveyor, where it passes around the sprocket 108, such trailing flight or tie kicker plate 130 will, in passing around the sprocket 108, thrust against the side wall

of the tie adjacent its end to firmly and positively pivot the tie about the fulcrum 102 and into a generally vertical position within the vertical infeed passage 94.

It will be noted that in the preferred embodiment but a single or leading conveyor flight 126 and but a single trailing flight or tie-kicker plate 130 are shown, though more may be employed if sufficient space is left between them for the ties T. In other words, the length of the conveyor must be such that its operative run 106 is somewhat longer than the ties to be placed thereon, it being contemplated that the tie will be operatively positioned on the conveyor at a time when the flights are disposed on the return run thereof or, if on the operative run, are at the discharge end thereof so as to leave ample space for positioning of a tie on the conveyor.

For maintaining a tie T operatively positioned on the conveyor in readiness to be picked up by the leading conveyor flight 126, there is provided a tie support in the form of a rigid platform 132 which is connected at 134 to the conveyor frame in position for abutting engagement with the lower end of a tie T which is placed on the operative run 106 of the conveyor. The tie support or platform 132 preferably has its outer end supported by chains 136 which extend diagonally downwardly from the frame 112 to resist downward swinging forces exerted by the ties.

It is to be noted that the inner edge of the platform 132 is spaced outwardly from the operative run 106 of the conveyor a sufficient distance to permit the conveyor flights 126 and 130 to pass without interference, though the spacing will be less than the thickness of the ties so that they must engage the abutment.

In the preferred embodiment of the invention it will be noted that the overall height of the mechanism may be appreciably reduced for ready passage through tunnels and under bridges during transport. Thus the boom 46, 56 may be swung downwardly to a position substantially no higher than the operator's cab. Similarly, the comparatively high tie infeed chute 22 is preferably formed in upper and lower sections which are hingedly interconnected at 138 so that the upper section may be swung downwardly to a substantially horizontal position as shown in broken lines in FIG. 1, by means such as the hydraulically actuated piston and cylinder unit 140 interconnected between brackets 142, 144 on the respective sections eccentrically to the hinge pivot 138. When in its downwardly swung or collapsed condition, the upper section of the chute may rest on a support 146, affixed to the vehicle frame.

As earlier mentioned, the ties T are fed downwardly into the comminutor C and are thereby reduced to chips, which then fall through an opening in the bottom of the comminutor casing 24 and into the conduit 34 connected to the intake of the blower B. The end of the conduit 34 remote from the blower casing 45 is open so as to permit the inflow of air beneath the comminutor housing 24 whereby to entrain the wood chips and carry them into the blower B for discharge through the preferably swivelled discharge spout 36. Manifestly, the spout 36 may discharge the chips into the bushes alongside the roadbed or, if desired, into a suitable receptacle.

In the operation of the invention, the vehicle 10, under the control of the operator, will normally be self-propelled along the railroad tracks until brought to a position opposite a tie or ties T which have been discarded and placed on the shoulder of the roadbed alongside the track. The articulated boom sections 46, 56 then may be manipulated to lower the tie grapple G to a position for gripping engagement with a tie. The tie grapple is actuated then to grippingly engage the tie adjacent one end thereof, whereupon the boom 46, 56 is then actuated to raise the tie and, with the tie T in a generally vertically suspended position, to bring it opposite and into registry with the operative flight 106 of the conveyor. By actuation of the rotary hydraulic motor 86, the tie grapple G is then ro-

tated to position one of the flat sides of the tie toward the upper run 106 of the conveyor, following which the tie is laid on the conveyor with its lower end resting upon the tie support or platform 132. At this time, the conveyor will be disposed in a position of rest with the flights thereof preferably on the return run of the conveyor to avoid any possible interference with such positioning of the tie.

Thereafter the grapple jaws 60-60 are disengaged from the tie and removed by suitable actuation of the articulated boom.

The fluid drive motor 124 of the conveyor is then suitably actuated under the control of the operator in conventional manner to commence upward movement of the operative conveyor flight 106, thus causing the leading conveyor flight 126 to pass downwardly around the drive sprocket 110 and then move upwardly into abutting engagement with the lower end of the tie, so that the tie is then moved upwardly on the operative run, and its upper end is thrust upwardly through the infeed opening 95 in the lateral side of the chute 22 across the vertical feed passage 94 of the chute and on to the sloping chute bottom 100.

It will be apparent that during movement of the leading conveyor flight 126 along the rectilinear portion of the operative run 106, it will be strongly reinforced by the immediately trailing abutments 127 and 128 against rearward angular deflection by the end of the tie, and will thus thrust the tie firmly upwardly into the chute. When the leading flight 126 approaches the discharge end of the conveyor and passes around the discharge sprocket 108, it will become disengaged from the end of the tie and normally will have only partially tilted the tie toward a vertical position about the fulcrum 102 defined by the lower end of the sloping chute portion, so that the end of the tie may then thrust downwardly into engagement with that portion of the conveyor chain between the flights 126 and 130 which is passing around the discharge sprocket 108. When this occurs, the trailing conveyor flight or kicker flight 130 in approaching and passing around the sprocket 108 positively abuts against the side wall of the tie T adjacent its end to firmly and positively pivot the tie about the fulcrum 102 to a substantially vertical position in which the lower end of the tie is completely freed of the conveyor and the tie is free for movement vertically downwardly through the feed passage 94 of the chute to be fed by gravity into the rotating comminutor head 26.

The action of the comminutor head 26, which is well-known, is such as to reduce the tie to small chips of wood which fall through the open bottom of the comminutor casing to be entrained in the rapidly flowing current of air within the conduit 34 and thus pneumatically conveyed to and through the blower B for discharge through the swivelled discharge spout 36 of the blower.

Having thus described my invention, I claim:

1. Infeed mechanism for delivering discarded railroad cross-ties into a rotary comminutor having a casing formed with an upwardly directed feed opening comprising: a guide chute above said opening defining a vertical feed passage communicating downwardly with the opening; said chute being formed with an infeed opening through one lateral side thereof; an endless conveyor having a vertically inclined operative run moving upwardly to the level of said infeed opening and thence laterally towards said opening; a flight on said conveyor for thrusting engagement with the lower end of a tie carried on and in alignment with the operative run of the conveyor whereby to project said tie into said opening and across said vertical passage; tie supporting and guiding means aligned with said operative run on the remote side of said vertical passage from the conveyor; said tie supporting and guiding means defining a fulcrum for the ties at one side of said vertical passage; and tie kicker means on said conveyor operative during its movement with the conveyor laterally towards said opening for tilting the

lower end of said tie about said fulcrum to a generally vertical position in said vertical passage.

2. Infeed mechanism as defined in claim 1, in which said tie supporting and guiding means comprises a sloping bottom of said chute aligned with said operative run on the remote side of said vertical passage from the conveyor and intersecting said vertical passage; the lower end of said sloping bottom at its juncture with said vertical passage defining said fulcrum.

3. Infeed mechanism as defined in claim 1, including a stationary tie support at the lower end of said operative run and out of the path of said conveyor flight for supporting engagement with the lower end of a tie placed on said operative run of the conveyor.

4. Infeed mechanism as defined in claim 1, in which said endless conveyor comprises a sprocket chain and relatively spaced apart sprockets supporting said chain and guiding it for movement in an endless circuit, one said sprocket being at the discharge end of said sprocket chain and guiding the said chain in its lateral movement towards said opening.

5. Infeed mechanism as defined in claim 1, in which said conveyor flight projects outwardly from the surface of the conveyor by a distance less than the thickness of a tie and said stationary tie support is spaced outwardly from the conveyor sufficiently to clear said flight but in a position to engage the end of a tie on said conveyor.

6. The combination defined in claim 5, in which said conveyor flight is carried by and projects normally outwardly from a link of said conveyor chain, and a flight support is carried by a following link for abutting engagement with the trailing face of said conveyor flight to resist rearward deflection thereof with respect to the travel of said conveyor.

7. Infeed mechanism as defined in claim 1, in which the side of said chute above said infeed opening is closed to confine the upper end of the tie against outward swinging movement.

8. Infeed mechanism as defined in claim 1, in which said chute is provided with an overhanging inclined guide portion above and extending parallel to said operative run of the conveyor and cooperating with said sloping bottom of the chute to define an inclined infeed passage intersecting said vertical feed passage and preventing downward tilting of the upper end of the tie.

9. Infeed mechanism as defined in claim 1, including a trough having a bottom along which said operative run

moves and relatively opposed side walls extending on opposite sides of the operative conveyor run in directions parallel thereto to retain the ties on said run.

10. Infeed mechanism for delivering discarded railroad cross-ties into a rotary comminutor having a casing formed with an upwardly directed feed opening, comprising: a guide chute defining a vertical feed passage communicating downwardly with said feed opening and a vertically inclined infeed passage intersecting said vertical feed passage, said inclined feed passage extending through one side of said chute to define an infeed opening; an endless conveyor having a vertically inclined operative run moving upwardly to the level of said infeed opening and thence laterally toward said opening; means at the juncture of said vertical and vertically inclined passages defining a fulcrum for tilting of said tie to swing it from said inclined passage into the vertical passage; and flight means on the conveyor for urging said tie lengthwise into said inclined passage and for then swinging it about said fulcrum into said vertical passage.

11. Infeed mechanism as defined in claim 10, further including a stationary tie support at the lower end of said operative run of the conveyor and located out of the path of said flight means for engagement with the lower end of a tie placed on said operative run of the conveyor; said conveyor flight means being disposed for movement in a path clear of said tie support for operative engagement with the end of the tie.

12. Infeed mechanism as defined in claim 10, in which said conveyor is of the chain type including a rigid frame and relatively spaced apart sprockets rotatably mounted on said frame for guiding said conveyor chain through its operative circuit.
